UNITED STATES PATENT OFFICE.

FRANK NEWKIRK, OF NEW YORK, N. Y.

DESIGN FOR A BOLSTER AND SHAM-HOLDER.

47,140.

Specification for Design.

Patented Mar. 23, 1915.

Application filed December 27, 1913. Serial No. 809,133. Term of patent 3½ years.

To all whom it may concern:

Be it known that I, FRANK NEWKIRK, a citizen of the United States, and residing in the borough of Brooklyn, city of New York, in the county of Kings, State of New York, have invented a new, original, and ornamental Design for a Bolster and Sham-Holder, and of which the following is a specification, reference being had to the accompanying drawing, forming part thereof.

The figure is a perspective view of a bolster and sham holder, showing my new design.

I claim:

The ornamental design for a bolster and sham holder, as shown.

FRANK NEWKIRK.
